UNITED STATES PATENT OFFICE.

CARL G. MUENCH, OF ST. PAUL, MINNESOTA.

CONCRETE BUILDING CONSTRUCTION.

1,417,553.

Specification of Letters Patent. Patented May 30, 1922.

Application filed September 29, 1920. Serial No. 413,550.

To all whom it may concern:

Be it known that I, CARL G. MUENCH, a citizen of the United States, residing at St. Paul, in the county of Ramsey and State of Minnesota, have invented certain new and useful Improvements in Concrete Building Constructions; and I do hereby declare the following to be a full, clear, and exact description of the invention, such as will enable others skilled in the art to which it appertains to make and use the same.

This invention relates to concrete building construction and has for its object to provide a concrete building having thermos-insulated walls, which will be simple and comparatively inexpensive to construct and more efficient in use than those heretofore proposed.

With this and other objects in view the invention consists in the novel details of construction and combinations of parts more fully hereinafter disclosed and particularly pointed out in the claims.

Referring to the accompanying drawings forming a part of this specification in which like numerals designate like parts in all the views:

Figure 1 is a diagrammatic cross sectional view of a wall embodying one form of the invention, showing the sheathing in place during construction;

Figure 2 is a perspective view of one of the thermal insulating core blocks shown in Figure 1;

Figure 3 is a diagrammatic cross sectional view of a wall, showing a somewhat modified form of insulating block;

Figures 4 and 5 are views similar to Figure 3 illustrating still further modified forms of wall construction.

Referring more particularly to the form of the invention shown in Figs. 1 and 2, 1 indicates a thermal insulating block preferably of felted cellulose fibrous material, which block is provided in the course of its manufacture with the integral lugs or projections 2, as will be clear from the drawings. The fibers composing the said block may be conveniently obtained from the waste products of the ordinary paper mill, known as wood pulp "tailings" and are of varying sizes, such as the coarse sliver like fibers 3, of from say 1/16 to 1/8 of an inch in diameter and from 3/8 to 5/8 of an inch long; the medium threadlike fibers 4, of from 1/50 to 1/32 of an inch in diameter,

and from 1/2 to 1 inch in length; and the fine hairlike fibers 5, of from 1/100 to 1/200 of an inch in diameter and from 1 to 2 inches long. In addition to these there may also be a fourth class composed of relatively short fine fibers, such as are commonly used for making paper, and which in the present instance act as a filler or binder.

By felting the above classes of fibers together by means of a suitable machine a board or block may be produced which is exceedingly porous and light, and is at the same time relatively strong and possesses excellent heat insulating qualities. In fact, it entrains an abnormal quantity of air and is a very close approximation to cork both as to its porosity and specific gravity, and also as an insulator.

In the development of concrete buildings a serious disadvantage has manifested itself, in that the concrete is a relatively good conductor of heat and cold, and therefore buildings constructed from such material have proven difficult to heat satisfactorily in winter, and conversely, exceptionally warm in the summer. However, by providing a core or base wall of blocks such as those above described, and suitably imbedding them in, or coating one or both sides thereof with concrete, a building may be obtained which will embody the rigidity and enduring qualities of the latter material while at the same time, possessing heat insulating qualities not to be found in those built under the methods previously proposed.

Accordingly, I propose to build up a substantially unbroken wall of blocks 1, and to associate therewith suitable forms or sheathing 6, see Figure 1. The said sheathing will be spaced from the body portion of the blocks 1, by the lugs or projections 2 thereon, and into this said space 7, a suitable mixture of concrete 8 may be poured in the usual manner. After the said concrete 8 has set, the forms 6 may be removed, leaving a poured monolithic cement wall having a core of heat insulating material.

The insulating material being composed of the individual fibers having the differing dimensions above disclosed, it of necessity is possessed of innumerable air cells, and therefore, it entrains or imprisons such an abnormal or large quantity of air that it has a heat insulating capacity equal to that of cork. It is also highly porous as above described, bonds with the plastic material, and

owing to the thorough felting or inter-weaving of the various classes of fibers above mentioned, and especially the relatively long thread-like and hair-like fibers, the blocks 5 possess sufficient strength to prevent them splitting into layers, as would be the case if only short fibers were used.

In the somewhat modified form of the invention illustrated in Figure 3, the dotted 10 lines indicate a hollow insulating block 1 in which the body portion, instead of being perfectly straight, is made zig zag or of corrugated cross section. This construction will of course add somewhat to the strength 15 of the core, and at the same time permit of a thicker layer of plastic material on each side thereof without increasing the length of the lugs 2. The joints between the adjacent blocks may be stepped or lapped, as 20 shown at 10 in said figure.

It will of course be obvious that if desired the lugs 2 may be omitted and in lieu thereof suitable spacing strips may be employed between the core and the sheathing 25 6 to provide spaces for the concrete 8. A wall constructed upon this principle is shown in Figure 4, wherein the hollow core blocks 1 instead of being provided with the outwardly projecting lugs are suitably recessed 30 as at 12 to provide additional bonds for the concrete 8. If desired, suitable tie wires or staples 13 may be run through the blocks 1 as shown to further strengthen the construction, although it is preferable to have 35 no heat conducting connections at all between the inner and outer layers of concrete.

In Figure 5, the hollow blocks 1 are provided with recesses 12 upon one side only 40 and are made with a tongue and groove joint 15 between adjacent blocks. In this case the inner layer of concrete is omitted, and a coat of plaster 16 is applied directly to the inner surface of the blocks 1. Suitable metal reinforcing material 17 may be imbedded in 45 the outer concrete 8, as shown.

The interior and exterior surfaces of the concrete walls illustrated may be treated in any desired manner after the forms 6 are removed. That is to say, they may be left 50 just as they set, or they may be suitably coated with plaster, stucco, or paint, as each

individual case may require. Further, the core blocks 1 may be suitably waterproofed, if desired, either by impregnation with 55 waterproofing substances during their manufacture, or by dipping in or spraying with oil or wax after they are formed.

By the term "continuous" as applied to the core, found in the claims, I mean that the 60 core extends throughout its length and breadth without interruption by other material, as opposed to the construction wherein in the individual blocks of said core are spaced apart and the spaces filled with some other material.

It is obvious that those skilled in the art 65 may vary the details of construction as well as the arrangement of parts without departing from the spirit of the invention and 70 therefore I do not wish to be limited to the above disclosure except as may be required by the claims.

What I claim is:—

1. A concrete building construction comprising a wall having a continuous core of fibrous felted material entraining an abnormal quantity of air, and coated on both sides with a plastic material and having interlocking connections between said fibrous and plastic materials, substantially as described. 75

2. A concrete building construction comprising a wall having a hollow continuous core composed of different sizes of fibers to provide numerous air cells and having 80 bonded to said core on each side thereof a plastic material, and said core provided with lugs to interlock with said plastic material, substantially as described. 85

3. A concrete building construction comprising a wall having a continuous heat insulating core zigzag in cross section provided with projections constituting interlocking means for the finished plastic layers, and said core coated on each side with 95 a plastic material adhering thereto, substantially as described. 90

In testimony whereof I affix my signature in presence of two witnesses.

CARL G. MUEENCH.
